UNITED STATES PATENT OFFICE.

VERNE MONROE, OF CAMERON, WEST VIRGINIA.

ROLLER SHEAVE.

Application filed October 19, 1927. Serial No. 227,334.

The present invention is directed to improvements in roller sheaves.

The primary object of the invention is to provide a device of this character more particularly designed for guiding a wire cable from its original reel or spool to the bull wheel of a drilling rig, the construction being such that the sheave can be quickly engaged with the cable and then anchored to the derrick.

Another object of the invention is to provide a device of this kind which will permit the cable to be effectively guided during the winding thereof without the likelihood of the same becoming kinked, the construction being extremely simple in construction, strong, and light in weight.

In the accompanying drawing:

Figure 1 is a view of a derrick showing the manner in which the cable is wound from the reel to the bull wheel of the drilling rig.

Figure 2 is a side elevation of the sheave.

Figure 3 is a sectional view on line 3—3 of Figure 2.

Figure 4 is a fragmentary view of a modified form of anchor.

The sheave consists of a member 1 of arcuate formation which includes a back 2 and side flanges 3, said flanges supporting the transversely disposed bolts 4, preferably five in number, and upon which are journaled the grooved rollers 5 which are provided with openings 6 for the introduction of a lubricant.

In order to anchor the member 1 to the frame 7 of the derrick 8 a pair of brackets 9 are provided which consist of integrally connected angularly disposed arms 10 and 11 which have their ends engaged upon the opposite faces of the flanges and are secured by certain of the bolts 4. These brackets will be obviously maintained in spaced relation and the arms 10 and 11 at their merging points are formed with circular openings 12 having restricted entrance slots 13, the purpose of which will appear later.

In order that the sheave can be anchored to the derrick a hook 14 is employed and has its shank swiveled to a head 15, the ends of which are provided with headed trunnions 16. These trunnions have flat faces 17 to permit the lugs to pass through the entrance slots 13, and upon turning the head 15 the faces 17 will assume a position as shown

in Figure 5, thus preventing the lugs from accidentally slipping from the openings 12. The hook 14 can then be engaged with the derrick upon attaching the same to a wire loop 18 or in any other manner found desirable. It will be observed that the hook 14 can be conveniently removed upon swinging the same to a position to permit the trunnions to pass through the slots 13, thereby permitting the cable to be passed between the brackets 9 for engagement with the rollers, whereupon the hook is replaced.

From the foregoing it will be seen that the cable 19 can be easily trained over the rollers 5 of the sheave and unwound from the reel 20 over the block pulley 21 for winding on the bull wheel 22, and owing to the radius of the member 1 the danger of the cable kinking during the winding thereof is positively eliminated.

Since the cable is under stress during the winding thereof it will be maintained in the grooves of the rollers and effectively guided in its travel.

Having thus described the invention, I claim:

1. A device of the class described, comprising an arcuate member including spaced side flanges, bolts supported by the flanges, rollers journaled on the bolts, brackets secured to certain of said bolts, and means for anchoring the brackets to a support.

2. A sheave of the class described, comprising an arcuate member including a back and spaced side flanges, bolts supported transversely of the member by the flanges, rollers located between the flanges and journaled on the bolts, brackets including angularly disposed arms, said arms having their ends fixed to certain of said bolts, and means secured between the brackets for anchoring the sheave to a support.

3. A device of the class described comprising a member having rollers supported thereby, brackets engaged with the member and having openings formed therein and having restricted slots communicating therewith, and a head having a hook swivelly connected thereto, said head having trunnions carried thereby, the said trunnions having flat faces to permit their passing through the slots for pivotal engagement in the openings.

In testimony whereof I affix my signature.

VERNE MONROE. [I. S.]
